BED GUARD MOUNTING

William A. Hillenbrand, Batesville, Ind., assignor
to The Hill-Rom Company, Batesville, Ind., a
corporation

Application September 1, 1937, Serial No. 162,043

3 Claims. (Cl. 248—226)

This invention relates to hinged and adjustable side guards for beds and the like and to brackets for such side guards.

The principal object of the invention is to pro-

vide a novel side guard, having a new side guard bracket, which may be easily and quickly attached to and detached from the variously shaped horizontal outer members of bed frames and the like.

10 Another important object is to provide such a guard which may be disposed, in a rigid upright position, along the side of the bed, above the frame thereof or may be readily swung to a lowered position, out of the way, below the frame.

Still another object is to provide a guard bracket, having latching and hinging means, which means do not project upwardly to a position above a bed mattress or bed coverings. Such 20 means, which do project above mattresses and the like, are frequently in the way, are apt to injure occupants of the beds and, because they project above mattresses and the like, may be too easily manipulated by the occupant. The 25 novel guard bracket herein disclosed is so disposed that children or patients, for instance, who should not manipulate the latching and hinging means, cannot readily reach such means and accidentally or otherwise cause the guard to swing 30 away from its guarding position. On the other hand, a person at the outside of the bed may readily manipulate such means, associated with the novel guard and guard brackets herein disclosed.

35 Another object is to provide a novel bed guard having attaching means therefor which is particularly sturdy.

Still another object is to provide a bed guard which does not require lifting when the guard is upright in order to latch it in a rigid vertical position nor in order to unlatch it when it is desired to swing it to an out-of-the-way position.

Another object is to provide such a guard, having means for securing the guard to a bed frame, including adjustment screws or nuts, which are easily accessible to a person outside of the bed, since they extend outwardly of the front portion of the adjustment means.

50 Other objects and advantages of the invention will be apparent during the course of the following detailed description, taken in connection with the accompanying drawings, forming a part of this specification and in which drawings:

55 Figure 1 is an elevation of a structure to which

the novel guard is attached and secured in a guarding position.

Figure 2 is a perspective view of a bracket, embodying a combined adjusting and bolting means, for association with a bed guard.

Figure 3 is a view partly in end elevation and partly in vertical section of the means shown in Figure 2, attached as shown in Figure 1, to a structure having a channel iron frame.

Figure 4 is a view, somewhat similar to Figure 10 5 3, illustrating the means associated with the guard, attached as in Figure 1, to a structure having an angle iron frame.

Figure 5 is a rear elevation of the means shown in Figure 4.

Figure 6 is a fragment of the means shown in Figures 2 to 5 inclusive, illustrating a bolt forming a portion thereof.

Figure 7 is a section substantially upon the line 7—7 of the means shown in Figure 4.

In the drawings, wherein for the purpose of illustration is shown a preferred embodiment of the invention and wherein similar reference characters designate corresponding parts throughout the several views, the letter A may designate a 25 structure, such as a bed to which the novel guard structure B is attached, which guard structure B may include the wall portion or guard element C and the attaching, adjusting and bolting means D for the guard element C.

The structure A, shown by way of example, is a conventional bed, having a frame, including an outer horizontally disposed side member or rail 11, raised above the floor and supported by a bed head 12 and foot 13. Upon the frame rest 35 the springs 14 which, in turn, may support a mattress 15. The side member 11 may be of channel-like cross section, as shown in Figure 3, where there are two paralleling, inwardly-extending, horizontal flange portions 16 and 17 and 40 a vertical web portion 18 joining the portions 16 and 17 and facing outwardly. In other cases, the side member 11 may be of angle-iron construction, as shown in Figure 4, where there is but one inwardly-extending horizontal flange 45 portion 16 and a vertical flange portion 18 joining the portion 16 and facing outwardly. However, the novel means D, to be later described, is adapted to be adjustably secured, as well, to other forms of side members associated with beds and 50 the like, as will be readily apparent, after said means D is described.

The guard structure B, which includes the wall portion or guard element C and the adjustable mounting bracket means D is preferably provided 55

assembled, as illustrated in Figures 1 and 3 to 6. However, the means D may be provided separately since it is quite readily attached to a suitable guard element.

- 5 As for the guard element C, it may comprise a tubular rectangular frame 20, having parallel side members 21 and 22 and paralleling end members 23 and 24 joining the side members 21 and 22. The length of this frame 20 is preferably somewhat less than the length of the structure A, and the height of the frame may vary, but it is preferred that it be less than the distance from the surface upon which the structure A rests to the bottom of the side member 11. 10 Spaced apart uprights 25 may join the side members 21 and 22 and be spaced from the end members 23 and 24. Depending upon the number of bracket means D employed with a guard structure C, the lowermost side member (designated as 15 22) is provided with a pair of perforations 26, with their axes substantially aligning and vertical. There are two of these axially aligning perforations for each means D employed.

The attaching, adjusting and bolting means D preferably comprises a bracket plate which includes a vertically disposed arm or plate portion 30, from the upper end of which may extend inwardly a horizontally disposed arm or rest portion 31, so that the portions 30 and 31 have an inverted L-shape. This arm or plate portion 30 is preferably provided with a vertically extending slot 32, spaced from the bottom of the arm or plate portion 30 as well as from the arm or rest portion 31.

- 35 Associated with the arm or plate portion 30 is an upper V-shaped clamp member 33. Preferably, this clamp member 33 includes a horizontal slide portion 34, having a longitudinally extending slot 35, a downturned jaw portion 36 at one end and a downturned arm portion 37 at the other end. The downturned portion 36 may be provided with a screw threaded perforation 38. So that the clamp member 33 may slide relative to the rest portion 31, a pair of spaced apart guide members or pins 39 may extend through the slot 35 and be rigidly secured, in any approved way, to the portion 31. Cooperating with the screw threads in the perforation 38 may be a thumb screw 40 which extends through the perforation 35 and bears, at its free end, upon the plate portion 30.

Also associated with the L-shaped bracket plate is a lower L-shaped clamp member including a slide or shank portion 41, adapted to slide vertically over a part of the inner face of the plate portion 30. This slide or shank portion 41 preferably differs from the plate portion 30 in being somewhat channel-shaped, as may be seen particularly in Figure 7, and to the web of which may be secured, in any approved way, such as by welding or soldering, a screw threaded projection 42, which extends from the outer face of the slide portion 41, facing the plate portion 30. This projection 42 may comprise a machine screw, with the head thereof secured to the slide portion 41. The projection 42 extends through the slot 32 in the plate portion 30 and is provided with a suitable cooperating means 43, such as a wing nut, so that the slide portion 41 may be fixedly secured in various vertically adjusted positions with respect to the plate portion 30.

To the upper end of the slide or shank portion 44 may be secured, as by welding, a horizontally disposed butt or jaw portion 44 paralleling and

facing the arm or rest portion 31 and paralleling the slide portion 34.

It will be noted in Figures 3 and 4 that the arm or rest portion 31 is not as long as the butt or jaw portion 44 and that the free end of the portion 44 is upwardly and inwardly turned upon itself so as to provide a hook-like projection 45. It will also be noted, particularly in Figure 5, that the greater portion of the upper clamp member 33 is to one side of the horizontally disposed jaw portion 44.

So that the slide or shank portion 41 will not swing from side to side, a guideway therefor may be provided. This preferably comprises a substantially U-shaped guide clip or member 46, with the central portion or web 47 welded or otherwise secured to the inner face of the arm or plate portion 30 and with the flanges 48 extending from said inner face and disposed to either side of the slide or shank portion 41, as may be seen 20 in Figures 5 and 7. Preferably, this guideway is disposed at the bottom section of the arm or plate portion 30 and has an arcuate cut-out 49 in its upper edge to accommodate the projection 42. The web portion 47 of the V-shaped guide 25 member 46 has a second function, for it spaces the slide or shank portion 41 from the arm or plate portion 30, although they may be in facing relation. Thus, when the means D is employed in association with an angle-iron side 30 member 11, there will not be any decided canting of the slide or shank portion 41 when the lower end of the vertical portion 18 of the angle-iron side member 11 is between the upper end of the slide or shank portion 41 and the arm or plate 35 portion 30, as illustrated in Figure 4. From Figure 3 it will be seen that the central portion 47 of the guideway 46 interferes in no way with the functioning of the bracket means when employed with a channel-iron side frame member. 40

Supported at one vertical edge of the bracket plate portion 30, opposite to that edge portion carrying the lower clamp member, and projecting outwardly from the plate portion 30 as shown in Figures 2, 3 and 7, is a hollow upright or standard 50 preferably formed from square tubing and including upper and lower hingedly connected sections 51 and 52 respectively. The lower section 52 may be rigidly secured to the plate portion 30 as by welding as shown in Figure 7. The upper section 51, when the sections 51 and 52 are in vertical axial alignment, extends upwardly above the rest plate 31 and is hingedly connected to the lower section 52 by a hinge 53 disposed at the outer or front wall of the upright whereby the upper section may swing outwardly and downwardly as shown in dotted lines in Figure 3 and is limited against inward swinging beyond a vertical position by abutment with the upper end of the lower upright section 52. The upper 50 section 51 is provided in its side walls, and adjacent its upper end, with a pair of horizontally aligning openings 54 for receiving the lowermost side member or rail 22 of the guard frame 20. This lower side member 22 may be rigidly secured 55 to the section 51 as by welding, and with the perforations 26 therein disposed axially of the section 51. Provided in the upper end of the section 51 is a perforation 55 which axially aligns with the perforations 26 and slidably receives a 70 releasing pin or rod 56 which is provided at its outer end with an eye 57 forming a hand hold. The inner end of the rod 56 projects into the hollow upper upright section 51 and is connected to a locking bolt or plunger 58 which has sliding 75

movement in the sections of the upright 50. This locking bolt 58 when in its lowered or locking position as in Figure 6, extends across the hinge line of the upright sections 51 and 52 and locks these sections in axial alignment so that the guard wall is held in rigid upright position. When the bolt 58 is raised by the rod 56 to a position wholly within the upper section 51 and above the hinge line of the sections, the guard wall is free to swing outward toward the operator and away from the bed.

So that this bolt 58 and rod 56 may be readily assembled within the upper section 51, the lower portion of the rod 56 may be initially straight and inserted into a socket 59, formed longitudinally in the upper end of the plunger or bolt 58, as the latter is inserted into the open end of the section 51. By drilling a hole in the front wall of the section 51, substantially as shown at 60 in Figures 2, 3 and 6, and drilling a hole 61 transversely of the bolt 58 to join the socket 59 when the bolt is positioned so as to align the hole 61 with the perforation 60, a suitable punch is inserted through the perforation 60 and hole 61 and being struck so that the rod is set, as shown in Figure 6, whereupon it will not become detached from the bolt 58.

The means D may be attached to the guard element C in several ways. For instance, the side member 22 of the frame 20 may be welded or soldered at the openings 54 to the means D or, even if not welded or soldered, the rod 56 will prevent both longitudinal movement of the guard element C as well as swinging movement thereof relative to the means D.

Preferably, for convenience, there will be provided left and right hand attaching, adjusting and bolting means D.

Various changes may be made to the form of invention herein shown and described, without departing from the spirit of the invention or the scope of the claims.

What is claimed is:

1. In a bed guard mounting, an angle-shaped bracket plate providing a horizontal rest portion and a depending vertical plate portion, said plate portion having a vertical slot, an upper U-shaped clamp member slidable on the rest portion, a clamping screw for the clamp member, a lower

L-shaped clamp member movable longitudinally and perpendicularly of the vertical plate portion, clamping means for the lower clamp member including a threaded member extending thru said slot, and means for supporting a guard wall on 5 the bracket plate.

2. A clamp for attachment to an angle rail including a first flange and a second flange or to a channel rail including a first flange, a web, and a second flange, said clamp comprising an angle 10 bracket including a first arm of a length less than the width of the first flange of said angle rail or channel rail, and a second arm of a length greater than the width of the second flange of said angle rail or the web of said channel rail, a 15 first jaw slidably carried by the first arm and extending therefrom for engagement with the first flange of said angle rail or channel rail, adjusting means for the first jaw, a second jaw including a shank portion disposed in inwardly 20 spaced relation to said second arm and a butt portion extending laterally from the shank portion, said shank portion being movable longitudinally and perpendicularly of said second arm to position said shank portion in engagement 25 with the second flange of the angle rail or to position said butt portion in engagement with the second flange of the channel rail, and adjusting means for the second jaw.

3. A clamp for attachment to an angle or channel rail, said clamp comprising an angle bracket including a first arm and a second arm, said arms for engagement with adjacent faces of a rail, an angular jaw including a shank portion inwardly 30 of said second arm and a butt portion, means 35 guiding said shank portion for movement longitudinally and perpendicularly of the second arm, said guiding means spacing the shank portion from the free end of said second arm, and means 40 adjustably connecting said shank portion and said second arm, said connecting means being spaced from said guiding means, for securing said butt portion in engagement with a rail, said shank portion being spaced by said guide means substantially parallel to said second arm of the 45 angle bracket upon engagement of said butt portion with the rail.

WILLIAM A. HILLENBRAND.
